SHEET METAL CONTAINER

Robert Nyden, Manhasset, N. Y.

Application January 11, 1941, Serial No. 374,093

2 Claims. (Cl. 220—43)

The present invention relates to sheet metal containers of the type usually employed for packaging medicinal products such as tablets or powder and the like. Such containers ordinarily include a shallow box body and a cover therefor which has depending flanged edges adapted to telescope over the body. The cover and body are normally fixedly hinged together along one side and have cooperating means on the opposite side for locking the container when closed. The cover flanges normally closely embrace the walls of the body for substantially their depth thereby producing a frictionally sealed package. In order to open the container, it is necessary to grasp the box in the fingers of one hand and pry open the lid with a fingernail of the other hand. This method of opening quite often jars the container, causing the contents to be disturbed or spilled.

It is the primary object of the invention to provide a container of the above character which may be readily and easily opened and which overcomes the foregoing limitations.

Another object of the invention is the provision of a container having a cover loosely hinged on opposite side walls to permit free movement of the rear edges as the container is opened and closed.

Other objects and advantages will become apparent during the course of the following description.

In the drawing:

Fig. 1 is a perspective view of a container illustrated in open position and embodying the principles of my invention;

Fig. 2 is an end elevational view of the container;

Fig. 3 is a fragmentary bottom plan view of one hinge corner of the container;

Fig. 4 is a sectional elevational view of the container with the cover partially raised;

Fig. 5 is a similar view with the cover in full opened position; and

Fig. 6 is a vertical sectional view through the container in the region of the hinge and is taken on line 6—6 of Fig. 2.

Referring to the drawing, my invention is embodied in a sheet metal container having a shallow substantially rectangular body 8 including a bottom 9 rounded at the corners, upstanding front and rear end walls 10 and 11 respectively and side walls 12 and 13. A cover 15 for the body includes a top 16 having continuous depending front and rear end walls 17 and 18 respectively, and side walls 19 and 20 respectively, which telescope over and closely embrace the body walls. 55

Cooperating cover latching means 21 on the front walls of the cover and body, retain the cover against accidental opening when in closed position.

The cover 16 and side walls 19 and 20 are provided at their juncture with an elongated internal shoulder 22 which terminates short of the front and rear walls and is adapted to bear against the upper edge of the side walls 12 and 13 for rigidly supporting the cover in parallel relation with the body. The rear end of the shoulder (Fig. 4) forms a fulcrum about which the cover is rocked during the initial opening movement by the application of squeezing pressure at any point along the rear edges of the cover and body.

The walls 12 and 13 are offset inwardly a slight distance as at 23 in the region of their rear ends and a pair of aligned outwardly formed projections 24 or protuberances are formed thereon to provide a part of the hinge connection between the cover and body. The projections extend outwardly a distance substantially equal to the depth of the offset 23. The hinge provides for substantial free movement of the cover on the body, complete separation thereof being prevented by a pair of inwardly turned flanges 25 pressed from the lower margin of the walls 19 and 20 and normally underlying the projections 24. As illustrated particularly in Fig. 2 the flanges are disposed adjacent the offset area 23 and prevent the raising of the rear edge of the cover by reason of their taking under the projections 24. A pair of inwardly extending ridges 26 (Fig. 5) formed in the walls 19 and 20 perpendicular to and adjacent the forward end of the flanges 25 are adapted to bear against the projections 24 when the cover is in opened position. The cover is thus prevented from becoming separated from the body. The side and end walls of both the body and cover are each of substantially uniform height, the loose hinge connection providing for lateral separation of the cover and body during opening in order that the rear wall of the cover may pass around and under the wall of the body. With the cover in closed position, the ridge 26 lies within the offset area and thus does not interfere with the closing of the cover.

Modifications may be resorted to within the spirit and scope of the appended claims.

I claim:

1. A sheet metal container comprising a shallow substantially rectangular body having continuous upstanding side and end walls, a cover for the body having continuous depending walls adapted to telescope over the walls of the body,

said walls of both the cover and body being of substantially uniform height, a pair of internal shoulders formed within the cover lengthwise of the side walls at their juncture with the cover for supporting it on the side walls of the body, one end of said shoulders forming a fulcrum about which the cover is initially rocked, inwardly offset areas at one end of each side wall of said body, a hinge connection for said cover and body comprising a pair of outwardly extending aligned projections formed in the side walls of the body, within the offset area, flanges formed on the lower margin of the side walls of the cover opposite said offset area and normally positioned below said projections, a pair of vertical ribs normally projecting into the offset areas inwardly from the projections, and cover latching means for separably connecting said cover and body when closed.

2. In a sheet metal container, a rectangular

body including a bottom and upstanding side and end walls, the side walls in proximity to their juncture with one of the end walls being offset inwardly, a pintle directed outwardly from each offset portion a distance no greater than the depth of the latter, a cover comprising a top and depending side and end walls adapted to be telescoped over the side and end walls of the body, each side wall of the cover having an internal horizontal rib along its lower margin at a point opposite the offset portion of the body side walls, and a vertical rib at a point opposite the inner end of the offset portion, means for limiting telescoping movement of the body and cover functioning with the side walls of the body as a fulcrum about which the cover is initially rocked, and means for separably connecting the free end of the body and cover when closed.

ROBERT NYDEN.
